CLAIM

The ornamental design for a fishing lure, as shown and described.

DESCRIPTION

FIG. 1 is a top plan view of a lure showing my new design of the present invention;

FIG. 2 is a side elevational view thereof, taken from the right side of FIG. 1, the opposite being a mirror image of the side disclosed;

FIG. 3 is a rear elevational view thereof;

FIG. 4 is a front elevational view thereof; and,

FIG. 5 is a bottom plan view thereof.
